COMBINED DISPLAY AND STORAGE TRAY FOR CUTLERY OR THE LIKE

Louis Kriegel, Flushing, N.Y., assignor to Joy Plastics,
Inc., New York, N.Y., a corporation of New York

Filed Mar. 12, 1968, Ser. No. 10,928

Term of patent 14 years

Int. Cl. D7—02

U.S. Cl. D44—29

FIG. 1

FIG. 3

FIG. 1 is a perspective view of a combined display and storage tray for cutlery or the like showing my new design, with the parts in assembled relationship;

FIG. 2 is a perspective view with the parts in exploded relationship;

FIG. 3 is a bottom plan view of the lower member; and

FIG. 4 is a bottom plan view of the upper member. I claim:

The ornamental design for a combined display and storage tray for cutlery or the like, as shown.
